[57] **CLAIM**

The ornamental design for a battery pack for a mobile radiotelephone device, as shown and described.

DESCRIPTION

FIG. 1 is a perspective view of a battery pack for a mobile radiotelephone device in accordance with the present invention;

FIG. 2 is a front elevational view of the battery pack of FIG. 1;

FIG. 3 is a back elevational view of the battery pack of FIG. 1;

FIG. 4 is a side view of the left side of the battery pack of FIG. 2;

FIG. 5 is a side view of the right side of the battery pack of FIG. 2;

FIG. 6 is an end view of the bottom of the battery pack of FIG. 2;

FIG. 7 is an end view of the top of the battery pack of FIG. 2; and,

FIG. 8 is a perspective view showing the insertion of the battery pack in a mobile radiotelephone device.

The broken line showing the mobile telephone device in FIG. 8 is included for the purposes of illustrating the environmental elements only and forms no part of the claimed design.
